DESIGN FOR A LANTERN BURNER

Antonio Menna, Newark, N. J., assignor to Lovell-Dressel Company, Inc., Arlington, N. J., a corporation of Maine

Application March 24, 1936, Serial No. 61,767

Term of patent 14 years

To all whom it may concern:

Be it known that I, Antonio Menna, a citizen of the United States, residing at Newark, Essex County, in the State of New Jersey, have invented a new, original, and ornamental Design for Lantern Burner, of which the following is a specification, reference being had to the accompanying drawing, forming a part thereof.

In the drawing—

Figure 1 is a side view showing a lantern burner
embodying my new design;

Fig. 2 is an end view thereof, and

Fig. 3 is a top or plan view thereof.

I claim:

The ornamental design for a lantern burner,
as shown.

ANTONIO MENNA.
